DESIGN FOR A SHOE SOLE

John A. Katz and Frank F. Hills,
San Francisco, Calif.

Application October 19, 1936, Serial No. 65,360

Term of patent 3½ years

To all whom it may concern:

Be it known that we, John A. Katz and Frank F. Hills, citizens of the United States, residing in the city and county of San Francisco and State of California, have invented a new, original, and ornamental Design for a Shoe Sole, of which the following is a specification, reference being had to the accompanying drawing, forming a part thereof.

In the accompanying drawing:

Fig. 1 is a bottom plan view of a shoe sole showing our design; and

Fig. 2 is a sectional view taken on the line 2—2 of Fig. 1.

We claim:

The ornamental design for a shoe sole as shown.

FRANK F. HILLS.
JOHN A. KATZ.
